UNITED STATES PATENT OFFICE

160,604

TOOTHBRUSH

Robert W. Hutson, Santa Clara, Calif.

Application January 13, 1950, Serial No. 7,190

Term of patent 14 years

(Cl. D9—2)

To all whom it may concern:

Be it known that I, Robert W. Hutson, a citizen of the United States, residing at Santa Clara, State of California, have invented a new, original, and ornamental Design for a Toothbrush, of which the following is a specification, reference being had to the accompanying drawing, forming a part hereof.

Fig. 1 is a perspective view of a toothbrush, showing my new design;

Fig. 2 is a top plan view of the same;

Fig. 3 is a side elevational view;

Fig. 4 is a view in front elevation; and

Fig. 5 is a view in rear elevation.

I claim:

The ornamental design for a toothbrush, substantially as shown.

ROBERT W. HUTSON.
